ALFONSO D. GATES, OF SURREY, WISCONSIN.

Letters Patent No. 96,099, dated October 26, 1869.

IMPROVEMENT IN PUMPS.

The Schedule referred to in these Letters Patent and making part of the same.

To all whom it may concern:

Be it known that I, ALFONSO D. GATES, of Surrey, in the county of Portage, and State of Wisconsin, have invented certain new and useful Improvements in Force-Pumps; and I do hereby declare the following to be a full, clear, and exact description of the same, reference being had to the accompanying drawings, which make part of this specification, and in which—

Figure 1 is an elevation of a pump, embracing my improvements;

Figure 2 represents a vertical longitudinal section of the pump, on an enlarged scale, the valve being shown as closed;

Figure 3 represents a similar section, the valve being shown as raised by its connection with the hollow plunger; and

Figure 4 represents a view of the under side of the hollow plunger, showing the cross-bar and spring-catch for sustaining and operating the valve-opener and closer.

My improvements relate to the construction of that class of pumps which receives and forces the water by a hollow plunger moving within a cylindrical case; and consist in the construction and arrangement of a device for opening and closing the valve by the movement of said plunger, as will be more fully hereinafter described.

In the accompanying drawings—

A represents the case, which is placed at the bottom of the well, cistern, or other place, so as to be immersed in the water, and provided with a cylindrical opening, of proper size, to receive a hollow plunger, B.

This case may be supported in its immersed position in any proper manner. Its lower end is fitted with a cylindrical core or stopper, C, also provided with a cylindrical opening of much less diameter than that of the case, to form a seat for the valve, and for the purpose of admitting the water into the case, and to receive a vertical stem, D, to which the valve is secured. The plunger is fitted to move within this case, so as to render it water-tight, and is of a length about equal to that of the case in which it is enclosed. It is also provided with a central opening, extending throughout its length, to receive and discharge the water. The upper end of the case is open, so as to admit of the movement of the plunger within said case.

This plunger is connected to a shaft, or follower, E, which extends above the case a suitable distance, to allow it to be operated by gearing mounted in a frame, F, placed above the cistern, or other place from which the water is to be forced.

This gearing consists of a rack, G, secured to the

shaft or follower E of the plunger, and a pinion, g, mounted on a short shaft or axis, H, supported in suitable bearings in the frame, and matching into the teeth of said rack.

On one end of this axis H is placed a ratchet-wheel, I, and upon the same end of the axis, a lever, J, is also placed, having its end forked, so as to embrace the ratchet-wheel, and to receive a dog, j, which may be thrown into and out of gear with the teeth of the ratchet, for the purpose of raising the plunger, and to allow it to be forced downward to discharge the water.

The dog j is held in gear with the teeth by means of a spring, k, as the plunger is being lifted, and held out of gear by a cord, l, attached thereto, and hooked over a pin, m, on the lever J, when the plunger is being forced down.

In the latter case, the lever is locked eccentrically with the ratchet-wheel I, by means of a pin passing through the lever into holes in the wheel. The plunger, however, may be provided with a weight, by which it may be forced down with or without the aid of the lever.

As the plunger is being lifted by the ratchet, dog, and wheel, it may be held up by means of a ratchet-pawl, p, binged to the base of the frame F, so as to fit into any one of a series of ratchet-teeth, q, in the side of the follower E, as shown by red lines in fig. 1, and thus prevent it from descending while the dog of the lever moves over the ratchet-teeth.

The discharging-pipe L moves with the plunger, and is connected to the upper end of its central opening. It rises above the frame, and is supported and guided in its movement by it.

These parts may be constructed and arranged as represented and described, or any other suitable devices for operating the plunger may be adopted, to suit the purposes for and position in which the pump may be used.

The packing, for rendering the plunger water-tight at the upper end of the case, consists of a leather ring, M, fitted between the plunger and the case, the latter being made flaring for that purpose, and is held in place by an annular follower, N, fitted around the plunger so as to bear upon said leather packing.

This annular follower is held down by means of four arms O, fitted in dovetail-notches on the exterior of the case, so that their upper ends extend over and upon the circular follower, which, of course, keeps the packing in place. The packing may be forced down, if necessary, by wedges intervened between the ends of the arms and the annular follower.

The particular feature of my invention, however, is the valve-opener and closer, which consists of a rod or bar, P, connected with and extending from the upper face of the valve, provided with a series of teeth,

of rounding form, and fitted within an opening in a cross-piece, R, at the lower open end of the plunger B, so as to move up and down within said plunger.

Its connection, however, with the plunger is not fixed, but is effected by means of a spring-tooth, a, fitted in the cross-bar R, through which the toothed rod P passes, so as to bite into the teeth of the latter, and thus effect a yielding connection between the plunger and the valve Q, the tooth being held in the notches of the bar by means of a spring, b.

To allow of the proper operation of the yielding connection of the plunger and the valve, the lower stem D of the latter must be of a length to admit of a movement of the valve above its seat, of about four inches, to allow the water to enter the case, and this movement is limited by a stop, c, at the lower end of said stem, coming in contact with the bottom of the valve-seat.

The lower valve-stem is slotted, in order to allow the water to enter freely around its sides and through its middle, while the lower end of the plunger is made flaring, so as to allow the water to enter freely into the plunger. The length of the toothed rod is sufficient to allow of the full upward stroke of the plunger, and still maintain its yielding connection therewith.

The operation of opening and closing the valve is as follows:

The plunger being down, and the valve closed upon its seat, the first four inches, or thereabout, of the upward movement of said plunger will lift the valve, by means of the yielding connection, and allow the water to enter the case, and as the plunger continues to rise, the spring-tooth a will yield, and slip over the rounding teeth of the bar P, and thus continue to hold the valve open while the plunger rises to the extent of its

upward stroke, during which the water, seeking its level, rises and fills the case.

The movement of the plunger is now reversed, and the first four inches, or thereabout, of its descent, carries also with it the valve Q down upon its seat C, thus closing it, and confining the water within the case. The yielding connection of the spring-tooth a then allows the plunger to readily descend and force the water up through it, and out of the discharging-tube L. This latter position of the parts is shown in fig. 2, while that of opening the valve by the ascent of the plunger, is shown in fig. 3 of the drawings.

This arrangement of opening and closing the valve by the yielding direct connection of the plunger therewith, I have found to be of great advantage, and to possess a power to force the water to a great distance.

Having thus described my invention,
I claim—

1. The hollow plunger B, united directly to the valve Q of the pump, by means of a yielding connection, for the purpose substantially as before described.

2. The lower valve-stem D, having a stop, c, for arresting the ascent of the valve, substantially as described, in combination with the yielding-connection of the valve and plunger, substantially as before described.

3. A valve, Q, having a notched or toothed bar, P, connected with the plunger, and a stem, D, connected with the seat of the valve, in the manner and for the purpose substantially as hereinbefore described.

In testimony whereof, I have hereunto signed my name.
